CONVEYER SYSTEM FOR SPOOLERS
AND THE LIKE

Gadsden E. Shand, Jr., Columbia, S. C.

Application September 1, 1950, Serial No. 182,823

7 Claims. (Cl. 198—60)

1

This invention relates to improvements in conveyor systems and more especially to an improved conveyor system for textile machinery, such as spoolers and the like.

It is well known, to those familiar with the art, that the placing of filled bobbins or quills on the spindles or creels of textile machines such as spoolers and the like is, at best, a costly and back-breaking task for an operator. Particularly wherein spoolers are concerned, the spoolers have been provided with bins extending longitudinally thereof adjacent which hand trucks containing the filled bobbins were usually positioned and the contents thereof dumped into the bin, the quills or bobbins then being selected by the operator and placed on the spindles provided therefor on the spooler.

It is evident that this would require considerable handling of the filled bobbins or quills and in the event of one of the bins adjacent the spooler being emptied, it would be necessary for the operator to select the filled bobbins from an adjacent bin thus delaying the donning or spindle loading operation as it is carried out over a considerable period.

It is therefore the primary object of the invention to overcome such defects through the medium of a continuously or intermittently driven conveyor which encircles the spooler and is provided in lieu of the usual bins at opposed sides of the machine and to further provide means for automatically feeding the filled bobbins to the continuously moving conveyor thus insuring that an ample supply of filled bobbins may always be available to an operator thus requiring a minimum of handling of the filled bobbins. The present apparatus eliminates the necessity of positioning trucks adjacent the spoolers for dumping the filled bobbins from the truck into the bins of the spoolers thus permitting the spoolers to be positioned more closely together than has heretofore been practicable, resulting in an additional saving in floor space.

It is another object of this invention to provide an improved conveyor for spoolers and the like comprising an endless trackway which encircles the spooler and in which an endless conveyor chain is mounted, there being suitable variable speed control means for imparting movement to the conveyor chain and this conveyor chain being provided with a plurality of spaced rigid substantially U-shaped trough supporting members each having a pair of transversely spaced uprising prongs thereon for supporting an endless trough of flexible ma-

2

terial such as cloth or rubber, the bottom of the trough being supported on the portions of said supports extending between the uprising portions thereof and the side wall portions of the trough being provided with a plurality of pockets into which the prongs are inserted to thus insure that the conveyor trough will move in fixed relation to the trough support members.

Some of the objects of the invention having been stated, other objects will appear as the description proceeds when taken in connection with the accompanying drawings in which—

Figure 1 is a top plan view of the improved conveyor system showing a hopper in association therewith for feeding a supply of bobbins thereto and showing the outline of a spooler, or the like, in phantom lines;

Figure 2 is a side elevation of the improved conveyor system looking up at the lower side of Figure 1, with many parts shown schematically;

Figure 3 is a vertical sectional view taken substantially along the line 3—3 in Figure 2;

Figure 4 is an enlarged fragmentary sectional plan view taken substantially along the line 4—4 in Figure 2, and showing the pockets formed at opposed sides of the trough which are provided for reception of the uprising prongs on the trough support members;

Figure 5 is an enlarged fragmentary elevation of the driving means for the conveyor with parts broken away and looking substantially along the line 5—5 in Figure 1;

Figure 6 is an enlarged vertical sectional view taken substantially along the line 6—6 in Figure 2;

Figure 7 is an enlarged fragmentary elevation, with parts in section, taken substantially along the line 7—7 in Figure 6 and showing the manner in which the conveyor trough supports are connected to the conveyor chain;

Figure 8 is a fragmentary view similar to the lower left-hand portion of Figure 7 but showing the means for connecting the trough support members to the conveyor chain in an open position;

Figure 9 is an enlarged vertical sectional view taken substantially along the line 9—9 in Figure 5.

Referring more specifically to the drawings, the numeral 10 designates an elongated textile machine, such as a spooler or the like, and this spooler 10 is shown as being circumscribed by an improved conveyor system broadly designated at 11. The conveyor system includes a substantially tubular conveyor or trolley track broadly

designated at 12 which is preferably of box-shaped cross-section, as best shown in Figure 6, comprising a bottom wall 13, vertical side walls 14 and inwardly extending top walls or flanges 15. The latter serve as load supporting runways on opposed sides of a centrally disposed slot 16, defined by the flanges 15, which extends longitudinally of the top of the track 12. This track 12 may be considered as endless except its continuity is interrupted for the driving means for imparting movement to the chain, to be later described, which is adapted to move along said track.

In order to provide for the driving means, to be presently described, a special section of track, designated at 12' (Figure 5) is interposed in the track 12, this special section corresponding to the standard section 12 except that a relatively long opening defined by the lower edges 17 of the side walls 14' of the special section of the track 12', these walls 14' being identical to the walls 14 of the track shown in Figure 6 (Figure 9). This opening 17 is provided in the special section of track 12' to provide the necessary opening for the driving means to pass along in driving relation to the conveyor chain. Suitable joint brackets 20, only one of which is shown in Figure 5, are provided to join the ends of this special section 12' with the coextensive standard section 12.

Referring to Figures 2 and 6, the standard section of track 12 is supported on a plurality of spaced legs 21, the lower ends of which are adapted to rest on a floor F and the upper ends of which are secured to the track 12, through the medium of a transverse angle bar 22 welded to the upper end of each of the legs 21 and being welded to the lower wall 13 of the track 12.

The conveyor chain, broadly designated at 25, is made up of alternating series of identical links 26 and identical connecting links 27, this conveyor chain being of a type substantially as shown in a patent to P. M. Hassler, No. 2,309,587 of January 26, 1943. Each of the alternating links 26 is provided with a pair of laterally spaced vertical wheels or rollers 30 which are of slightly less diameter than the distance between the bottom wall 13 and the flanges 15 of the trolley track 12 and which normally ride upon the bottom wall 13 although, at times, they may ride in engagement with the lower surfaces of the flanges 15 due to the torque caused in the supports, to be later described.

The rollers or wheels 30 associated with each of the alternating links 26 are fixed on opposed ends of an axle 31 which is rotatably mounted in the links 26, the side plates of these links 26 being spaced apart from each other between the spaced rollers 30. The links 26 and 27 are pivotally connected to one another by suitable pins 32 and each connecting link 27 carries a horizontally disposed guide roller 33 of a diameter only slightly smaller than the inside width of the track 12 but greater than the overall width of the alternating links 26, so that this horizontal wheel is adapted to have rolling contact with the side walls 14 of the track 12 and prevents contact of the vertically wheeled links 26 with said side walls.

Each of the alternating links 26 also has a transverse attachment or fastener pin 34 mounted therein and disposed above and in spaced relation to the axle 31 of the wheels 30, by which means the trough support members, to be later described, are connected to the conveyor chain 25.

Any desired driving means may be provided for imparting movement to the conveyor chain 25, the particular type of driving means shown in Figures 1, 2 and 5 being substantially the same as that shown in said Patent No. 2,309,587. There are many types of variable speed transmissions which may be employed in association with the driving unit, to be presently described, such as a type manufactured by Reeves Pulley Company, Columbus, Indiana or a so-called Master Speed-ranger manufactured by the Master Electric Company, Dayton, Ohio. The particular type of variable speed transmission shown in Figures 2 and 5 is of the type manufactured by the Master Electric Company and includes an electric motor 37 which drives a variable speed transmission 38, both the electric motor 37 and the variable speed transmission 38 being suitably secured to the lower surface of a horizontally disposed drive unit support plate 39 which is substantially rectangular and is supported on legs 40 which rest on the floor F. The electric motor 37 transmits rotation, through the reduction gear or variable speed mechanism 38, to a sprocket wheel 41 which transmits rotation, by a sprocket chain 42, to a larger sprocket wheel 43 mounted on a transversely extending drive shaft 44 disposed at one end of the mechanism.

Secured to this drive shaft 44 are two laterally spaced driving sprockets 45 over which pass suitable driving chains 46. These driving chains 46 are endless and also pass around two idler sprockets 47 mounted on a transverse shaft 48 disposed at the other end of the driving mechanism. To provide for taking up any undesirable slack in the driving chain 46, the shaft 48 is mounted in bearings 49 which are adapted to be moved horizontally between the upper and lower ways 51 of a guide frame member 52 at each end of the shaft 48, the guide frame 52 being suitably secured, as by bolts 53, to the lower surface of the plate 39. An adjusting screw 54 functions as an adjustable spacing strut between each slideable bearing 49 and the inner end of its associated frame 52.

As shown in said Patent No. 2,309,587, every fourth link on each of the chains 46 is provided with an inturned flange 57 and each link disposed midway between said every fourth link is provided with an ear 60, one end of a pivoted driving dog 61 being pivotally connected between the ears 60 on adjacent links of the two chains 46 and the flanges 57 (Figure 9) being provided to support one end of each of the dogs 61, the dogs 61 each having a pair of rollers 63 rotatably mounted thereon and projecting from opposed sides of the dogs 61. These rollers 63 are normally supported by the flanges 57 when the dogs are moving in the plane of the lower reaches of the chains 46.

Referring again to Figures 5 and 9, there will be observed a driving dog guide plate 64 which rests upon the upper surface of the driving unit support plate 39 and opposed ends of which are provided with inclined portions 64a, 64b, there being suitable openings, not shown in the present drawings but clearly shown in said Patent No. 2,309,587, into which the inclined portions 64a, 64b of the plate 64 project and also through which the driving chains 46 and the sprocket wheels 45 and 47 project and also through which the dogs 61 move as the chains 46 move in a clockwise direction in Figure 5.

The inclined portions 64a and 64b of the drive track 64 function as a receding cam or track sur-

face which determines the point at which the driving dogs are engaged and release their driving engagement with the conveyor chain 25, the dogs being adapted to move into position between the side plates of the alternating links 26 and into engagement with the axle 31 of the corresponding rollers or wheels 30 for propelling the conveyor chain 25 from left to right in Figure 5. Thus, a variable speed drive means is provided for effecting movement, continuously or intermittently, of the conveyor chain 25 along the trolley track 12 provided therefor. Since the structure of the driving mechanism is clearly shown and described in said Patent No. 2,309,587, a further detailed description thereof is deemed unnecessary. It will be noted that the driving mechanism shown in Figures 2 and 5 is inverted from the position in which it is shown in said patent and the trough supporting members, to be presently described, are connected to the conveyor chain 25 by means of an attachment pin identical to the pin to which the attachment member 53 of said patent is connected to its corresponding conveyor chain and it is with a conveyor chain and a driving mechanism of the type heretofore described that the present invention is particularly adapted to be associated although it need not be restricted to this particular type of chain or driving mechanism.

The forked or U-shaped trough support members are each broadly designated at 70 and each includes a pair of spaced uprising prongs or arms 71 and 72, which are bent inwardly towards each other at their lower portions to form horizontal portions 73, the portions 73 being welded together at their juncture (Figure 6) as at 73a and then each of the portions 73 being extended downwardly as at 74, these portions 74 being removable secured to the upper ends of a pair of links 75 and 76 by any suitable means such as a bolt 74a. These links 75 and 76 are identical except being turned opposite hand relative to each other and these links are provided with respective notches 77 and 78 defining respective hook portions 81 and 82, these notches 77 being disposed at the proximate edges of the links 75 and 76 when they are swung apart from each other at their lower ends as shown in Figure 8.

The links 75 and 76 also have respective projections 83 and 84 on the lower ends thereof. The notches 77 and 78 extend inwardly and upwardly at an angle relative to the axes of the links 75 and 76 so that when the links 75 and 76 are moved into closed position, as shown in Figure 7, the notches 77 and 78 may engage the fastening pin 34 provided therefor in association with each of the alternating links 26 and the projections 83 and 84 at the lower ends of the links 75 and 76 will engage opposed sides of the axle 31. After the links 75 and 76 have been swung inwardly to occupy the position shown in Figure 7, the bolt 74a is tightened to secure the links 75 and 76 in a rigid position in engagement with the pin 34 and to also hold the upstanding arms 71 and 72 of the top support member 70 in a fixed vertical position relative to the links 75 and 76.

In order to insure that the links 75 and 76 and the arms 71 and 72 of the trough support members 70 may retain a substantially vertical position as they are moved along the track 12 by the conveyor chain 26 and, also, to assist in supporting the weight of the members 70 and the trough, to be later described, and its contents, the links 75 and 76 are provided with respective bores 87 and 88 which, upon swinging the

links 75 and 76 to the position shown in Figure 7, will be disposed in coinciding relationship with each other and which are provided for the reception of an axle in the form of a bolt 89 on which a pair of rollers or wheels 90 and 91 are rotatably mounted.

These wheels 90 and 91 are disposed adjacent the remote sides of the links 75 and 76 when they are in assembled position, as shown in Figure 6, and are adapted to ride upon the flanges 15 of the track 12. It is preferred that the rollers or wheels 30, 33, 90 and 91 be provided in the form of anti-friction or ball bearings, in which instance, the inner races thereof would be fixed on the corresponding axles. However, it is to be understood that any desired type of wheel or roller may be employed in the capacity of the rollers 30, 33, 90 and 91.

The trough support members 70 support an endless substantially U-shaped flexible trough broadly designated at 95 and which may be made of a fabric, a synthetic material or rubber as desired. This flexible trough 95 is preferably pre-formed to include a bottom 96, inner and outer side walls 97 and 98 respectively, these side walls being termed as inner and outer side walls with respect to the machine 10 which the improved conveyor system 11 encircles.

Referring to Figure 6, it will be observed that the side walls 97 and 98 of the trough 95 extend upwardly from the bottom 96 and are turned outwardly and downwardly upon themselves to form down-turned overlapping portions 100 and 101 on the respective walls 97 and 98. The portions of the overlapping down-turned portions 100 and 101 of the walls 97 and 98 disposed between the uprising arms or prongs 72 and 71 respectively of adjacent supports 70 are adhesively or otherwise secured to the outer surfaces of the corresponding walls 97 and 98 to form pockets 102 at each side of the trough 95 which are adapted to loosely receive the upper ends of the uprising arms or prongs 71 and 72. It is evident that, in the event of the trough 95 being made of a fabric of similar material, the overlapping portions 100 and 101 of the respective walls 97 and 98 may be suitably stitched to form the pockets 102 heretofore described.

It is thus seen that, upon movement of the conveyor chain 25, from left to right in Figures 2 and 7, the trough supporting members 70 will move in unison therewith and the pockets 102 in the side walls of the trough 95 will also cause the trough 95 to move in fixed relation to the prongs or arms 71 and 72 of the trough support members 70.

In the event of the trough 95 being made of a flexible non-resilient material, such as fabric or the like, it is evident that a certain amount of slack must be provided in the side walls thereof between adjacent trough support members 70, and the slack in the outer wall 98 will be taken up, as shown in Figure 1, as the cloth 95 moves through the arc shown adjacent opposed ends of the textile machine 10.

On the other hand, if the trough 95 is made of a resilient material such as rubber, there need not necessarily be any slack in the side walls 97 and 98 between adjacent trough support members 70 because the outer wall 98 may stretch as it moves through the arc at opposed ends of the machine 10.

Since the trough 95 may move continuously or intermittently around the textile machine 10, the trough 95 need only be loaded with filled

bobbins or quills from a single point and, in order to insure that the rate of supply of bobbins to the trough 95 may be in accordance with the speed at which the trough 95 is moved and, in turn, in accordance with the speed at which the bobbins are removed from the trough 95 and placed on the spindles of the machine 10, I have provided a hopper broadly designated at 105 (Figures 1, 2, and 3), which is open topped and includes side walls 106, 107, end walls 108, 109 and an inclined bottom 110, the bottom 110 preferably being made of a light sheet metal or other flexible material.

A suitable vibrator 111 is suitably secured to the lower surface of said bottom 110 of the hopper 105. Any desired type of vibrator may be employed in the capacity of the vibrator 111 for vibrating the bottom 110 of the hopper 105, a suggested type of vibrator being an electrical-magnetic vibrator of a type shown and described in a United States Patent to G. D. Aldord, No. 2,180,189 of November 14, 1939. The hopper 105 may be supported on suitable standards 113, the lower ends of which rest on the floor F and the upper ends of which are suitably secured, as by screws 114, to the lower surface of the bottom 110 of the hopper 105. The front wall 109 of the hopper 105 is provided with a discharge opening 115 therein through which filled quills or bobbins 117 may be discharged, the bobbins being dumped into the hopper 105 from the usual trucks used in the textile industry. Suitably secured, as by welding, to the exterior surface of the front wall 109 of the hopper 105 is an inclined tapered tubular chute 120 which is provided to direct the bobbins 117, which move along the chute 120 by gravity, to the opened top of the trough 95, the vibrator 111 and the opening 115 in the front wall 109 of the hopper 105 serving to regulate the flow of the bobbins down the chute 120 and into the trough 95.

It is thus seen that I have provided an improved conveyor system, particularly for use in association with textile machines of a type onto which bobbins are to be placed by operators, and which may be moved continuously or intermittently around the machine and to which a continuous supply of filled bobbins may be directed in accordance with the speed at which the bobbins are used from the conveyor.

It might be stated that most spoolers doff empty quill or bobbins automatically and are provided with conventional conveyor means for conveying the bobbins away from the spooler.

In the drawings and specification, there has been set forth a preferred embodiment of the invention and, although specific terms are employed, they are used in a generic and descriptive sense only and not for purposes of limitation, the scope of the invention being defined in the claims.

I claim:

1. A conveyor system for textile machinery such as spoolers and the like, comprising an endless stationary track encircling said machine and provided with an endless slot, endless movable means disposed below said slot, means for driving the endless movable means, a plurality of horizontally spaced upstanding rigid trough support members extending through said slot and connected to said movable means at the lower ends thereof and having rollers thereon disposed above said track for rolling upon said track to support said trough support members, an endless flexible trough carried by said trough support

members and having a plurality of pockets at opposed sides thereof, said trough support members each having at least one upstanding prong thereon and the upper ends of said prongs extending into the corresponding pockets on said trough whereby said trough may move in unison with the movable means in said track.

2. A conveyor system for textile machinery, such as spoolers and the like, comprising an endless horizontally disposed tubular track encircling said machine and provided with an endless slot, endless movable means disposed within said track, means for driving the endless movable means, a plurality of horizontally spaced upstanding rigid trough support members each having a downwardly projecting leg extending through said slot and connected to said movable means at the lower end thereof and having rollers thereon disposed above the track for rolling upon said track to support said trough support members, an endless flexible trough carried by said trough support members and having a plurality of pockets at opposed sides thereof, said trough support members each having at least one upstanding prong thereon and the upper ends of each of said prongs extending into the corresponding pockets on said trough whereby said trough may move in unison with the movable means in said track, said trough extending in a slack manner between adjacent trough support members so as to permit the trough to pass through an arc of relatively short radius.

3. A conveyor system for textile machinery, such as spoolers and the like, comprising an endless tubular track encircling said machine and provided with an endless slot, endless movable means disposed within said track, means for driving the endless movable means, a plurality of upstanding rigid trough support members each having a downwardly projecting leg connected to said movable means at the lower end thereof and having rollers thereon disposed above the track, one on each side of the slot for rolling upon said track to support said trough support members, an endless trough made of a flexible material mounted on said trough support members and having a plurality of pockets at opposed sides thereof, said trough support members each having at least one upstanding prong thereon and the upper ends of said prongs extending into the corresponding pockets whereby said trough may move in unison with the movable means in said track, said resilient material permitting the trough to be taut between adjacent prongs of the trough support members and permitting the outer portions thereof to pass through an arc of relatively short radius, stretching the outer wall of said trough in so doing.

4. A conveyor system for textile machines on which bobbins are adapted to be manually placed in a yarn processing operation comprising an endless trough of flexible material substantially U-shaped in cross-section adapted to encircle a textile machine, a plurality of trough supporting members disposed beneath the trough and each having a pair of spaced upstanding prongs thereon, pockets on opposed sides of the trough and into which the upper portions of said prongs extend, an endless stationary tubular track disposed beneath the trough and having an endless longitudinally extending slot in the upper edge thereof, rigid means on each of the trough supporting members extending through said slot in the track, a roller mounted on each side of the rigid means and resting on the upper surface of said track

a continuously moving element disposed within the confines of said track and means connecting the lower ends of said rigid means to the continuously moving element in said track for supporting and imparting continuous movement to the trough supporting members and the trough.

5. A conveyor system for textile machines on which yarn filled bobbins are adapted to be manually placed comprising an endless substantially U-shaped trough of flexible material adapted to extend through a circuitous route around the machine, means for introducing a continuous supply of filled bobbins to a given point in said trough, means for moving said trough past the said point, means supporting said trough comprising a plurality of spaced trough support members, each having at least one uprising prong thereon, a frame supporting the lower ends of the trough support members, a plurality of pockets on the outer surface of at least one of the walls of said trough and being penetrated by the corresponding prongs on the trough support members and movable means connected to the lower ends of said trough support members for imparting movement to the trough supports and the trough, the means for introducing the filled bobbins to said conveyor comprising a hopper having a chute extending therefrom to a point above the conveyor, and means for imparting vibratory movement to the hopper to cause the bobbins to move through said chute by gravity.

6. An endless conveyor comprising an endless trough of flexible material, means supporting the trough comprising a plurality of spaced trough support members, each having a pair of transversely spaced upstanding prongs thereon, pocket means on the outer surfaces of the walls of said trough and being penetrated by the prongs, a horizontal portion extending inwardly from the lower end of each of said prongs for supporting the bottom of said trough, downwardly extending portions integral with said horizontal portions, a pair of links pivotally secured to the downwardly extending portions, an endless stationary track extending in a horizontal plane beneath the trough and being substantially tubular in cross-section and having a longitudinally extending slot therein, an endless conveyor chain mounted for movement along said trough, means for imparting movement to the conveyor chain, said conveyor chain having a plurality of spaced links thereon provided with transverse fastener pins, the lower ends of said links having notches

extending from the common centers thereof outwardly with respect to each other, whereby the lower ends of said links may be spaced from each other and swung to a closed position in alignment with each other and the notches may engage the pins in the corresponding links for connecting the lower ends of the links to the fastener pins of the chain, means penetrating said links in a horizontal plane above the track for holding said links in fixed relation to each other and at least one roller rotatably mounted on said means penetrating said links and adapted to ride upon the upper surface of said track for supporting the trough support members and the trough.

7. A conveyor system for textile machines on which bobbins are adapted to be manually placed in a yarn processing operation comprising an endless substantially U-shaped trough, of flexible material adapted to encircle said textile machines, said trough having its side walls turned downwardly upon themselves at their upper edges to form overlapped portions, means dividing portions into a plurality of pockets, a plurality of trough supporting members disposed beneath the trough and each having a pair of spaced upstanding prongs thereon, said prongs extending into said pockets, an endless stationary tubular track disposed beneath the trough and having a longitudinally extending slot in the upper edge thereof, rigid means on each of the trough supporting members extending through said slots in the track, a continuously moving element disposed within the confines of said track and means connecting the lower ends of said rigid means to the continuously moving element in said track for supporting and imparting continuous movement to the trough supporting members and the trough, said rigid means having at least one roller mounted thereon above the track and adapted to roll on the upper side of the tubular track.
